United States Patent Office

Des. 192,944
Patented May 29, 1962

192,944

JAR OR SIMILAR ARTICLE

Frank B. Busch and William E. Fillmore, Toledo, Ohio, and Ira H. Miller, Lambertville, Mich., assignors to Owens-Illinois Glass Company, Toledo, Ohio, a corporation of Ohio

Filed Mar. 7, 1961, Ser. No. 64,173

Term of patent 14 years

(Cl. D58—25)

The characteristic feature of the design resides in the particular configuration of the neck portion above the shoulder as shown in full lines on the drawing.

We claim:

The ornamental design for a jar or similar article, substantially as shown and described.
